UNITED STATES PATENT OFFICE

111,853

DESIGN FOR A COMBINED GLOBE AND STAND

William E. Johnson, Chicago, Ill., assignor to Rand McNally & Company, a corporation of Illinois

Application July 15, 1938, Serial No. 78,519

Term of patent 14 years

To all whom it may concern:

Be it known that I, William E. Johnson, a citizen of the United States of America, residing at Chicago, in the county of Cook and State of Illinois, have invented a new, original, and ornamental Design for a Combined Globe and Stand, of which the following is a specification, reference being had to the accompanying drawing, forming a part thereof, in which:

Figure 1 is a side elevation of the globe stand;

Figure 2 is a top plan view thereof; and Figure 3 is a side elevation at right angles to that of Figure 1.

The dominant features of my design reside in the portions shown in full lines.

I claim:

The ornamental design for a combined globe and stand, as shown and described.

WILLIAM E. JOHNSON.
